United States Patent Office.

WILLIAM B. SCAIFE, OF PITTSBURG, PENNSYLVANIA.

REISSUED

Design No. 4,224, dated July 12, 1870.

DESIGN FOR A KITCHEN-BOILER.

Reissued May 25.

The Schedule referred to in these Letters Patent and making part of the same.

To all whom it may concern:

Be it known that I, WILLIAM B. SCAIFE, of Pittsburgh, in the county of Allegheny and State of Pennsylvania, have invented and produced a new and original Design in Kitchen-Boilers, which is clearly shown in the accompanying drawing, which forms part of my specification.

My design consists of a kitchen boiler, the body A which is cylindrical in form, with the upper end B forming a section of a sphere, and the bottom C forming a section of a hollow sphere.

The contour of the kitchen-boiler, which constitutes my design, is clearly shown in the accompanying drawing, sheets A and B, Figures 1 and 2, in which—

A represents the body of the boiler;
B, the upper end; and
C, the bottom.

I, J, and K represent pipes.
e, f, g, and h, in fig. 2, Sheet B, represent openings for the pipes.

What I claim is—

The design for a kitchen-boiler, herein described, substantially as shown in the accompanying drawings.

W. B. SCAIFE.
